UNITED STATES PATENT OFFICE.

HARRY WEARNE, OF RIXHEIM, GERMANY.

DESIGN FOR WALL-PAPER.

SPECIFICATION forming part of Design No. 32,076, dated January 2, 1900.

Application filed December 7, 1899. Serial No. 739,582. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a strip of wall-paper embodying my design.

The leading feature of the design consists in a lattice scroll having reverse curves located between borders of irregular outline made up of conventionalized flowers and leaves, and bouquets of flowers, leaves, and buds located at the convexed portions of the scroll.

The minor features of the design consist in outer borders representing lines upon which sprays appear supported and sprays located ²⁰ between the intermediate and the outer borders.

Having thus described my invention, I claim as new and desire to secure by Letters Patent—

The design for wall-paper as herein shown and described.

HARRY WEARNE.
